UNITED STATES PATENT OFFICE.

FRANK B. MERRY AND JESSE D. WARE, OF SAVANNAH, GEORGIA.

TURNING AND FLUTING MACHINE.

1,175,969.

Specification of Letters Patent. Patented Mar. 21, 1916.

Application filed May 28, 1915. Serial No. 30,939.

To all whom it may concern:

Be it known that we, FRANK B. MERRY and JESSE D. WARE, both citizens of the United States, both residing at Savannah, in the county of Chatham, State of Georgia, have invented certain new and useful Improvements in Turning and Fluting Machines, of which the following is a specification.

- 10 This invention relates especially to machines for making columns or posts of wood to give to them a round, tapered, or other desired form and to form longitudinal grooves, flutes or ribs thereon for ornamental purposes, and the object of the invention is to provide a machine for these purposes which is simple in construction, easily operated and which will perform its functions with uniformity and exactness.
- 15 In carrying out our invention, we provide a machine having the general form and characteristics of a lathe, being provided with a bed on which head and tail stocks of usual form are mounted, and the lathe is driven in any suitable way. On brackets extending from the lathe-bed is supported a shelf on which is mounted a lathe-carriage-carrier which is pivotally connected with the shelf and which is controlled in its movement by
- 20 a pattern secured to the shelf and engaging a roller connected with the lathe-carriage, to which is also connected a rod connected with a weighted lever which holds the roller in engagement with the pattern. The lathe-carriage is mounted on the carrier and is adapted to move therewith toward and from the work. The carriage is provided with a nut which engages a screw-shaft within the carrier and this shaft is connected with driving pulleys for moving the carriage back and forth longitudinally of the machine. A horizontally arranged shaft is mounted in suitable bearings on the shelf and extends through the carriage which
- 25 moves endwise thereon. To this shaft is keyed a rotary cutter for turning the work to the desired shape, either cylindrical or tapered, and the carriage is also equipped with a rotary cutter for forming grooves,
- 30 flutes or ribs in the work or for giving an octagonal or other polygonal form thereto.
- 35 The fluting cutter is attached to a radially arranged shaft and is mounted in bearings in a swinging frame whereby the cutter may be brought down upon the work or may be withdrawn therefrom. On said radial shaft is secured a friction roller which engages a disk keyed to the horizontally arranged shaft and through which a rotary motion is given to the fluting cutter. The construction is such that when the fluting cutter is brought down upon the work the friction roller firmly engages the friction disk and the cutter is thereby rotated, but when the fluting cutter is moved away from the work it ceases to rotate. The machine is first operated to give the desired shape to the work by means of the turning cutter, the fluting cutter being then out of operative position, and then the fluting cutter is moved in such manner as to operate on the work thus shaped. In order to suitably ornament the upper portion of the column, we provide a cutter mounted in a frame which may be swung toward and from the work and held in contact therewith in such manner as to form a bead thereon or to give other suitable shape thereto.
- 40 Other features of our invention, together with certain details of construction, will be hereinafter specified.
- 45 In the accompanying drawings: Figure 1 shows a side elevation of a machine embodying our improvements with some of the parts broken away. Fig. 2 shows a top plan view thereof, with parts broken away. Fig. 3 is a view on an enlarged scale, and in section, showing particularly the manner of mounting the cutters in the lathe-carriage. Fig. 4 is a detail view, showing particularly the cam used for moving the roller on the fluting cutter shaft into engagement with its driving disk. Fig. 5 is a detail view of the cutter employed for forming a bead or other such ornament on the column. Fig. 6 is a detail view of the fluting cutter. Fig. 7 is a view on an enlarged scale and in transverse section of the machine. Fig. 8 is a

detail perspective view of a part of the cutter carriage-carrier.

The frame of the machine may be of any suitable construction. The lathe-bed A is shown as being supported on legs a , suitably braced at a' . The head-stock B and tail-stock B' may be of the usual kind, the mandrel of the head-stock being provided with fast and loose pulleys C, C', as usual. Brackets D, projecting laterally from the machine-frame, support a shelf E, on which is mounted a carrier F for the lathe-carriage G, which supports the cutters. The carrier F is shown as being in the form of a long narrow hollow structure, pivotally connected at f to the shelf E and provided with a casting H (Fig. 8), bolted at h (Fig. 7) to the sides of the carrier. This casting is formed with a recess h' and with a downwardly extending part h^2 , which extends through an opening in the shelf and connects with a horizontally arranged part h^3 , carrying a clamping device h^4 . By this means the carrier F may be held on the shelf E. When the devices h^4 are loose the carrier is still prevented from being raised away from the shelf but said carrier is free to swing to a limited extent on its pivot f , for a purpose hereinafter described, but by means of the devices h^4 the carrier may be held against a pivotal movement.

A pattern I is attached to an angle-iron I', bolted to the shelf E, and this pattern extends horizontally from one end of the machine toward the other. The pattern of course corresponds with the shape of the article to be produced. The carriage G carries a roller g, engaging the pattern, and this roller is held against the pattern by a weight J carried by a lever j, pivoted at j' , and connected by a rod J' to the carrier F in the manner shown in Fig. 7. Inasmuch as the carrier is pivoted at one end, as indicated at f , the weight tends to draw the opposite end of the carrier toward the work.

The lathe-carriage G is formed with a downwardly projecting lug g' , which is formed as a nut and engages a horizontally arranged screw-shaft K, mounted in suitable bearings on the carrier F and provided with pulleys, L, L', L² for driving it in opposite directions. By this means the lathe-carriage may be moved back and forth endwise of the machine, being supported in such movements by the carrier F on which it slides longitudinally.

The rotary cutter M for turning the work X is mounted on a shaft N, carrying a belt pulley O. The shaft is grooved at n and the hub of the cutter is connected with the shaft by keys n' in such manner that the cutter, while rotating with the shaft, is free to slide thereon. The shaft N extends across the recessed upper ends of posts or pillars P beneath the caps p and one of the posts

supports a sleeve Q which is held firmly in place on said post.

The grooving or fluting cutter R is secured to a radial shaft r, carried by a swinging frame S, mounted to turn on the sleeve Q. This frame has arms s through which the shaft r extends and one end of the shaft carries a roller s', which bears at times on a friction disk T keyed at t to the shaft N rotating therewith and sliding endwise thereon. The frame S has secured to it at u an arm U carrying a bolt u', engaging a stationary cam U' fixed to the sleeve Q. The cam is formed with a recess u² to receive the head of the bolt u', at which time the roller s' does not press tightly against the disk T but when the bolt is withdrawn from the recess of the cam and engages the flat face thereof the roller s' presses firmly against the disk T and the cutter shaft is rotated. It will therefore be understood that the work in the rough is placed between the head and tail stocks and rotated. A pattern I of suitable form is secured to the machine and rotary movement is given to the shafts K and N while the cutter-frame S is held on its support T' in such position as to hold the fluting cutters away from the work. As the shafts rotate the cutter M turns the work gradually from one end to the other, giving to it a form corresponding with the pattern used. Said cutter, in the machine shown, moves gradually from the tail stock toward the head stock of the lathe and when the pattern is of the shape shown in Fig. 2 a taper is given to a portion of the work, the cutter being gradually moved toward the axis of the work while it is moving toward the tail stock. After this is done the belts may be shifted and the cutter-carriage may be returned to starting position, and if it be then desired to flute, groove or similarly ornament the work the frame S may be swung from the position shown by full lines in Fig. 7 to that shown by dotted lines therein in order to engage the work. Before doing this, however, the driving belts of the head-stock are shifted so as to stop the rotation of the work and the work should then be locked against rotary movement while the grooving operation is in progress.

In Fig. 2 we have shown how grooves are formed in the cylindrical portion of the column. At this time the carrier F should be disposed parallel with the axis of the lathe and should be held firmly in place during the operation. The screw-shaft K causes the carriage to move from one end of the column toward the other while the shaft N imparts a rotary movement to the fluting cutter. When the end of a groove is reached the frame S may be swung back and the screw may be reversed to return the carriage to starting position. In order to properly space the distance between the grooves or

flutes we preferably form the fast pulley C with a plurality of concentric annular perforations c adapted to receive a pin c' on a lever C² pivoted to the lathe-bed. By these 5 devices the work may be held in the desired position while being grooved and may be moved to the desired extent to space the grooves or flutes on the work at the proper times.

10 It is sometimes desirable to form a bead on the upper part or neck of a column or to otherwise ornament it in a similar way. For this purpose we employ a cutter V of suitable shape, carried by a swinging frame 15 V', pivoted at v to an adjustable bracket v' attached to the lathe-bed. The frame V' is provided with a handle v² and it is formed with grooves to receive the cutter V which is clamped in the frame by a bolt v³. In 20 order to hold the cutter in proper relation to the work we employ a cam W pivoted to the frame V' and having a cam surface w which bears on the work. This cam may be adjusted and then rigidly fixed to the frame 25 V' by a bolt w'.

We have shown in the drawings one specific way of carrying out our invention. The machine is adapted to form columns, posts and other articles of various sizes, of 30 various shapes, and with different kinds of ornamentation. The general shape of the article is governed by the form of the pattern employed. By means of the rotary cutter M, the movement of which toward 35 and from the axis of the work is governed by the pattern, the column may be made partly cylindrical and partly tapered or wholly cylindrical or wholly tapered. When flutes, beads or grooves are formed 40 longitudinally in the article the pattern is not necessarily employed as these flutes may be formed in a direction parallel with the axis of the work, but it is obvious that the grooves may be formed in an inclined direction if a suitable pattern is employed. It is also obvious that by employing suitable cutters longitudinal beads may be formed instead of grooves or channels, and it is also possible to give to the article an 45 octagonal or other polygonal form by employing a suitable cutter in place of the cutter R, illustrated in the drawings.

50 While the machine is especially intended for working on wood some features of the invention may be employed in metal working machines.

We claim as our invention:

1. The combination with a lathe for supporting and rotating the work, of a lathe- 55 carriage-carrier pivotally connected at one end with the lathe frame and extending from end to end thereof alongside of the work, a lathe carriage mounted on the carriage and movable longitudinally thereon,

means for moving the carriage back and forth longitudinally on the carrier, a longitudinal cutter actuating shaft mounted in bearings on the lathe carriage above the carrier, means for rotating said actuating shaft, a cutter rotating with said actuating shaft 70 and movable endwise thereon with the carriage a pattern on the lathe frame, connections between the pattern and the lathe carriage and means for holding the carriage in engagement with the pattern. 75

2. The combination with a lathe for supporting and rotating the work, of a lathe-carriage-carrier pivotally connected at one end with the lathe frame and extending from end to end thereof alongside of the work, a lathe carriage mounted on the carrier and movable longitudinally thereon, a screw shaft mounted in bearings in the carrier and operatively connected with the carriage, a longitudinal cutter actuating shaft 80 mounted in bearings on the lathe carriage above the carrier, means for rotating said actuating shaft a cutter rotating with said actuating shaft and movable endwise thereon with the carriage, a pattern on the lathe frame, a roller on the carriage and means for holding the roller in engagement with the pattern as the carriage moves longitudinally on the carrier. 85

3. The combination with a lathe for supporting and rotating the work, of a lathe carriage, means for moving it back and forth longitudinally alongside of the work, a longitudinal cutter actuating shaft mounted in bearings in the carriage, means for 90 rotating said actuating shaft, a cutter rotating with said actuating shaft about its axis and movable endwise thereon with the carriage, a radial cutter carrying shaft, a swinging frame in which it is mounted and 95 which is mounted to move about the axis of said actuating shaft, gearing for connecting said radial shaft with said actuating shaft and means for operatively connecting the radial shaft with the cutter actuating 100 shaft when said radial cutter carrying shaft is brought into operative relation with the work. 105

4. The combination with a lathe for supporting and rotating the work of a lathe 115 carriage carrier, a lathe carriage mounted thereon, means for moving the carriage longitudinally on the carrier alongside of the work, a rotatable cutter actuating shaft mounted in bearings on the carriage, a turning cutter carried by said shaft rotatable therewith and movable with the carriage endwise thereon, a grooving cutter, a radial shaft on which it is mounted, gearing for connecting said radial shaft with said cutter-actuating shaft, a swinging frame supporting said radial shaft, and which is mounted to turn about the axis of said actu- 120 125

ating shaft, a cam supported by the carriage, and an arm carried by the swinging frame provided with a device engaging the cam whereby the swinging frame when turned is moved longitudinally on the actuating shaft to cause an operative connection between the actuating shaft and the radial shaft.

In testimony whereof we have hereunto subscribed our names.
